UNITED STATES PATENT OFFICE.

ELBARTUS D. CURTIS, OF CHICAGO, ILLINOIS.

DOOR-OPERATING MECHANISM.

941,132.

Specification of Letters Patent. Patented Nov. 23, 1909.

Application filed August 12, 1908. Serial No. 448,081.

To all whom it may concern:

Be it known that I, ELBARTUS D. CURTIS, a citizen of the United States, and a resident of Chicago, in the county of Cook and State 5 of Illinois, have invented certain new and useful Improvements in Door-Operating Mechanism, of which I do declare the following to be a full, clear, and exact description, reference being had to the accompanying 10 drawings, forming part of this specification.

The present invention has for its object to provide improved mechanism whereby sliding doors may be easily shifted from the 15 doorways which they normally close, and the invention consists in the features of improvement hereinafter described, illustrated in the accompanying drawings and particularly pointed out in the claims at the end 20 of this specification.

My invention is particularly well adapted for use in connection with lumber drying kilns, or like structures, in which heavy doors are employed, these doors being arranged 25 for removal from in front of the doorways by means of a common rail that extends along and usually at the top of the several doorways and serves as a track for the travel thereon of the carrying rollers that support the doors. It is highly desirable 30 that a simple, effective means be provided whereby the doors, while in normal position to close the doorways, shall be independent of and away from the track, so that the track shall be unobstructed for the 35 passage along it of any one of the series of sliding doors, and to provide simple and efficient means whereby the doors may readily be placed onto and supported by the track, so that the doors can be moved laterally from in front of their doorways and in 40 front of or beyond adjacent doors. This desideratum is most effectually accomplished by my present invention, in which each of 45 the several doors is provided with its individual carrying rollers adapted to be placed upon and then travel on the common supporting rail or track, or to be removed therefrom when the door is to be brought to 50 its normally closed position.

It has been heretofore proposed to provide various means whereby heavy sliding doors could be shifted laterally along a common rail or track and past other doors of the

structure adjacent thereto. Thus, in one 55 prior form of apparatus, the common track or rail is provided with a single traveling carrier by which any one of a series of doors can be transported along the common track and in front of the adjacent closed doors. 60 In another form of apparatus, designed for a like purpose, the doors have been provided with movably supported carrying rollers, the supports of these rollers being such that after the door has been lifted by supplemental mechanism, the carrying rollers can be swung outward away from the door and over the common track or rail, so that, upon the release of the lifting mechanism, the 65 rollers should rest upon the track or rail 70 and sustain the door thereon, in manner permitting it to be shifted laterally in front of or past other doors.

My invention is designed to provide more simple and effective door operating mechanism than those heretofore employed and, 75 with this end in view, I provide each door with means whereby it may be lifted and swung outward from its doorway, so as to permit its carrying rollers to rest upon the 80 common track.

In the accompanying drawings I have shown my invention as applied to a series of lumber drying kilns, but it will be readily understood that the invention is equally applicable 85 for operating sliding doors of various other structures, such as furnaces, railway cars or the like.

Figure 1 is a view in front elevation of a series of dry kilns having my improved door 90 operating mechanism applied thereto. Fig. 2 is a view in horizontal section on line 2-2 of Fig. 1. Fig. 3 is a view in horizontal section on line 3-3 of Fig. 1. Fig. 4 is an enlarged view in vertical section on line 4-4 95 of Fig. 1. Fig. 5 is a view similar to Fig. 4, but showing the door in partially closed position. Fig. 6 is a view similar to Figs. 4 and 5, but showing the door completely open.

In the drawings, A, B, C and D designate 100 a series of lumber dry kilns arranged side by side, the division walls between these kilns being designated as a, b and c. As shown, there are three rails E leading into each of the kilns, these rails being adapted to support the trucks whereon the lumber will be piled. 105

To the top portions F of the several kilns

are attached a series of outwardly and downwardly extending brackets G to which is secured a rail H that extends in front of the several doorways and constitutes the common track whereon the doors will be moved in lateral direction. In the drawings, I have illustrated two complete doors J and J' and portions of other similar doors J² and J³, these doors being alike in construction and 10 being each equipped with the same operating mechanism.

To each of the doors J, J', etc., there is secured, preferably adjacent its upper edge, the supporting rollers 2, these rollers being 15 adapted to travel upon the common track H, when the doors are moved outward by mechanism embodying my invention. Upon each door there is provided means whereby such door may be shifted from the closed position 20 shown in Fig. 4 to the open position shown in Fig. 6 of the drawings and, while details of this mechanism may be varied widely without departure from the scope of the invention, I prefer to employ the general features 25 of construction to be next described.

Upon each door there is mounted a pair of rock shafts 4 and 5 that are shown as journaled in suitable bearings 6 at or adjacent the edges of the door. I prefer to employ 30 two rock shafts, as shown, and to connect these shafts for unison movement by means of a link 7 that is united to the central crank portions 8 of the shafts. The ends of each of the shafts 4 and 5 are provided 35 with crank arms 9 and, to secure a more effective unison movement of the shafts, a link 10 may extend between the crank arms 9 at one or both ends of the shafts. One of the shafts, and, preferably the lower shaft 40 5, has fixed thereto a bail or handle 12 whereby the shafts will be shifted in manner to be presently described.

At the front of each partition wall a, b and c, between the kilns, there is provided 45 suitable means adapted to coöperate with the shifting mechanism on the doors. Preferably, such means consists of plates 15 having seats or sockets 16 opening forwardly and adapted to receive the cranks 9 of the 50 shafts 4 and 5. Preferably, each plate 15 is a channel plate and each of its outwardly projecting flanges is formed with a seat 16, so that one pair of plates will serve for co-operation with the cranks 9 at the adjacent 55 ends of two doors.

From the construction of parts as thus far defined, it will be seen that when a door is in closed position, the crank arms 9 of its shafts 4 and 5 will rest at the bottom of the 60 seats 16 of the plates 15 and the weight of the door being thrown upon the crank arms 9 will cause the door to be tightly held against its jamb, the crank arms 9 at such time extending approximately to the angle

shown in Fig. 4. If, now, it is desired to 65 shift a door, the attendant will grasp the bail or handle 12 and swing it downward, as indicated by the arrow in Fig. 4. The effect of this downward movement of the bail 12 will be to turn the shafts 4 and 5 and to 70 cause the door to be raised slightly and swung forwardly until its carrying rollers 2 rest upon the track H, as seen in Fig. 5. The downward movement of the bail 12 being continued slightly, the free ends of the 75 cranks 9 will come opposite the open portions of the seats 16 and the door may then be manually swung outward to the position shown by dotted lines in Fig. 5 and by full lines in Fig. 6. The weight of the door will 80 then be supported entirely by the carrying rollers 2 on the track H and the door can be shifted laterally in front of an adjoining door, or as far as may be desired. When a door is to be restored to closed position, it 85 will be brought opposite its doorway and the bail 12 will be shifted so that the free ends of the crank arms 9 will be in position to engage the seats 16 of the plates 15, and the door will be pushed inward until the crank 90 arms 9 are within the seats 16. The bail 12 will then be swung upward, thereby causing the shafts 4 and 5 to lift the carrying rollers 2 from off the track H and to swing the door from the open position shown by full lines 95 in Fig. 5 to the closed position shown by Fig. 4.

In order to enable a door to be accurately positioned in front of its doorway, so that the crank-arms 9 will enter the seats 16 of 100 the plates 15, when the door is pushed inward, I prefer to provide the means next to be described: In front of each doorway and at a slight distance therefrom are placed one or more pairs of vertically disposed 105 rollers 20 that are mounted upon upright studs or pins suitably bolted to the floorway of the structure, or otherwise conveniently supported, and, with very broad doors, I prefer to employ two pairs of such rollers, 110 as shown in the drawings. Each door is provided adjacent its bottom with means to coöperate with the rollers or guides 20 in positioning the door so that its crank-arms 9 shall come opposite the seats 16 of the 115 plates or brackets 15. As shown, each door has attached to its front, adjacent its bottom edge, two cam-shaped centering devices 21 that project forwardly a sufficient distance beyond the front of the door, so that 120 when a door has been brought opposite its appropriate doorway, the centering devices 21 will contact with the vertical rollers or guides 20 and, when the centering devices 21 are between the rollers or guides 20, they 125 will tend to check the door in proper position to insure the accurate setting of the crank-arms 9 into the sockets 16 of the plates

or brackets 15 when the door is pushed inward. It will be understood, of course, that if a door is being moved laterally for any considerable distance, its lower end may be 5 pushed slightly inward, so that the centering devices 21 shall not contact with the vertical rollers or guides 20, but, as the door reaches a point in front of its doorway, the contact of the centering devices 21 with the 10 rollers 20 will insure the accurate location of the door in central position.

It is manifest that the precise details of construction above set out may be varied widely without departure from the scope of 15 the invention, and that features of the invention may be employed without its adoption as an entirety. Thus, for example, while I prefer to use supporting rollers for the doors, shoes, such as are sometimes employed for freight car doors, might be employed, particularly if the doors to be shifted are not very heavy.

Having thus described my invention, what I claim as new, and desire to secure by Letters Patent, is:—

1. The combination with a structure having a doorway and having a track extending across said doorway, of a door provided with rollers mounted in fixed relation there- 30 to and normally disengaged from the track, and means mounted upon the door whereby said door may be shifted outwardly and inwardly to place said rollers upon or remove them from said track.

35 2. The combination with a structure having a doorway, of a track parallel with the structure, a door, track rollers carried by said door and normally disengaged from, but engageable with the track, and means mounted on the door and engageable with the structure for shifting the door outwardly from the doorway onto the track or inwardly from the track back to the doorway.

45 3. The combination with a structure having a doorway and having a track extending across said doorway and having sockets or bearings adjacent said doorway, of a door provided with rollers or supports normally disengaged from said track and means mounted upon the door and adapted to engage said sockets or bearings whereby said door may be lifted and moved outwardly to place said rollers upon said track and remove them therefrom to shift the door to closed position.

4. The combination with a structure having a doorway and having a track extending across said doorway and having sockets or 60 bearings adjacent said doorway, of a door provided with rollers or supports normally disengaged from said track, crank-arms mounted upon said door and adapted to engage said sockets or bearings and means

whereby said crank-arms may be turned to 65 cause them to lift and move outward the door in order to place its rollers upon the track.

5. The combination with a structure having a doorway and having a track extending across said doorway and having sockets or bearings adjacent said doorway, of a door provided with rollers or supports normally disengaged from said track, a rock shaft mounted upon said door and provided 70 with crank-arms at its ends adapted to enter and engage said sockets or bearings and means whereby said rock shaft may be turned to cause the door to be lifted and moved outward to place its rollers upon the 75 track or to return the door to closed position.

6. The combination with a structure having a doorway and having a track extending across said doorway and having sockets or bearings adjacent said doorway, of a door provided with rollers or supports normally disengaged from said track, a rock shaft mounted upon said door and provided 85 with crank-arms adapted to enter and engage said sockets or bearings and means whereby said rock shaft may be turned to shift the door inwardly and outwardly, said rock shaft being so mounted upon the door that when the door is in closed position, the 90 crank-arms or rock shaft will extend inwardly and above a horizontal plane.

7. The combination with a structure having a doorway and having a track extending across said doorway and having sockets or bearings adjacent said doorway, of a door provided with rollers or supports normally disengaged from said track, parallel rock shafts mounted upon said door and provided with crank-arms at their ends 100 adapted to enter and engage said sockets, said rock shafts being connected together and means whereby said rock shafts may be turned to shift the door inwardly and outwardly.

8. The combination with a structure having a doorway, and having a track extending across said doorway, and having open sockets or bearings adjacent said doorway, of a door provided with rollers or supports 115 normally disengaged from said track, a plurality of rock shafts connected together and mounted upon said door, said rock shafts being provided with crank-arms at their ends to enter and engage said sockets or 120 bearings and a bail or handle whereby said rock shafts may be turned to cause said door to be moved outward or inward in order to move its rollers or supports onto or away from the track.

9. The combination with a structure having a doorway and having a track extending across said doorway, along which track

the door can slide, of means for locating the door in accurate position in front of its doorway, comprising a double inclined guide projecting forwardly from the door and vertically disposed rollers located in front of the doorway to coöperate with said guide upon the door.

10. The combination with a structure having a door-way, of a track adjacent said door-way, a door having supports mounted in fixed relation thereon and arranged to engage said track to sustain the door therefrom, said supports being disengaged from said track in the closed position of the door, 15 and means for bodily shifting said door from the door-way onto the track and back to the door-way.

11. The combination with a structure having a door-way, of a track adjacent said door-way, a door having rollers or supports fixed in position thereon and normally disengaged from, but engageable with said

track to sustain the door therefrom, of means for guiding said door upwardly and outwardly to place said rollers on the track and 25 upwardly and inwardly from the track back to the door-way.

12. The combination with a structure having a door-way, of a track adjacent and parallel to said door-way, a door having rollers 30 or supports fixed in position thereon and normally disengaged from, but engageable with said track to sustain the door therefrom, of means for bodily lifting and guiding said door in a curved path upwardly, 35 outwardly and downwardly from the door-way onto said track and upwardly, inwardly and downwardly from said track back to said door-way.

ELBARTUS D. CURTIS.
